VALVE SEAT GRINDER STONE CARRIER

Leroy F. Densmore, Kenosha, Wis., assignor to
Snap-On Tools Corporation, Kenosha, Wis.

Application May 1, 1941, Serial No. 391,285

8 Claims. (Cl. 51—241)

This invention relates to valve seat grinding machines and more particularly to valve seat grinder stone carriers, although certain features thereof may be employed with equal advantage for other purposes.

It contemplates more especially the provision of a valve grinding stone carrier assembly having improved heat dissipating expedients conducive to better operation, longer wear and increased efficiency.

Numerous types of valve grinding stone carrier assemblies have heretofore been proposed, and many of these are expensive in construction, develop appreciable heat owing to high speed rotation relative to guide pilots and otherwise prove unsatisfactory from a functional standpoint. Assemblies of this type that involve a sleeve bearing that rotates therewith relative to a pilot serving as a positioning guide. This relative rotation between a relatively long sleeve and a pilot at high speeds, generates appreciable heat that must be effectively dissipated. It is intended, therefore, to provide effective heat dissipating expedients permitting relative rotation of the sleeve bearing relative to the pilot or guide without elevating the temperature of the coating elements to any detrimental degree.

One object of the present invention is to improve the construction and simplify the operation of devices of the character mentioned.

Another object is to provide improved means for maintaining the inner and outer sleeves of a stone carrier in relative rotation with a pilot or guide without elevating the temperature of the coating elements to a detrimental degree.

Still another object is to provide improved means for maintaining the inner sleeve of a valve grinding stone carrier, rotatable relative to the pilot or guide customarily used in conjunction therewith without developing any detrimental degree of heat that would impair operating efficiency and longevity.

A further object is to provide improved heat dissipating means in a valve grinding stone carrier to maintain a satisfactory temperature under conditions of prolonged high speed operation.

A still further object is to provide improved heat dissipating expedients between the outer and inner sleeve of a valve grinding stone carrier assembly.

Still a further object is to provide an improved interiorly fluted sleeve construction for valve grinding stone carriers to render them serviceable at high speeds without any detrimental

elevation in temperature under prolonged conditions of high speed operation.

Other objects and advantages will appear from the following description of an illustrative embodiment of the present invention.

In the drawing:

Figure 1 is a side view in elevation of a driver operatively connected to a valve grinder stone carrier with a portion shown in section to clarify the knuckle connection therebetween.

Figure 2 is a front view in elevation of a grinding stone embodying features of the present invention.

Figure 3 is a sectional front view in elevation of a valve grinding stone carrier embodying features of the present invention.

Figure 4 is a sectional view taken substantially along line IV—IV of Figure 2.

Figure 5 is a sectional view taken substantially along line V—V of Figure 2.

Figure 6 is a sectional view taken substantially along line VI—VI of Figure 2.

Figure 7 is a top plan view of a valve grinding stone carrier shown in Figures 1 and 2 showing the knuckle engaging socket.

The structure selected is illustrated in connection with a power hand driver 10 that terminates in a polygonal knuckle 11 having its sides converge to a point 12 so that its largest diameter is removed or spaced therefrom. The driver knuckle 11 is adapted to be telescopically received in a correspondingly sized polygonal socket 13 broached or otherwise provided in a tubular tool holder ring 14. The tool holder ring 14 is provided with a cylindrical surface 15 of somewhat smaller diameter than the larger sleeve recess 16 which terminates in a peripheral shoulder 17 serving as a limit therefor. The cylindrical surface 15 with its shoulder 17 are provided in an elongated tubular exterior sleeve 18 that is pressed or otherwise telescoped over an internal sleeve 19.

To this end, the inside bore 20 of the outer sleeve 18 substantially corresponds with the exterior diameter of the internal cylindrical sleeve 19 to provide for a tight or pressed fit therebetween. To preclude any possible separation between the tubular cap 14 and the outer sleeve 18, diametrically opposed pins 21, in this instance two, are disposed radially through somewhat smaller and aligned apertures 22—23 provided in the cap 14 and outer sleeve 18, respectively, for press-fit engagement to connect the ring 14 with the outer sleeve 18. This precludes any separation between the driving ring 14 and the outer sleeve 18 so that the latter will rotate responsive

to corresponding rotation of the driver knuckle 11 that is a complement of the socket 13.

The outer sleeve 18 is cylindrical in configuration and has an annular groove 24 exteriorly provided proximate to the lower end thereof. The annular groove 24 has inwardly converging sides 26—27 and with the annular groove 24 present a plurality of circumferentially spaced rectangular openings 28, in this instance six in number. The annular groove openings 28 communicate with longitudinally extending vanes, flutes or slots 29 provided along the interior bore 20 thereof to contact the confronting exterior cylindrical surface of the inner sleeve 19.

The longitudinally extending slots 29 (Figures 5 and 6) extend toward the socket 13 to communicate with radially extending apertures 30 provided through the outer sleeve 18 (Figure 2) so that there will be a constant circulation of air between the outer sleeve 18 and inner sleeve 19 for intake through the rectangular openings 28 in the annular groove 24 and discharge through the radial apertures 30. This circulation is effected responsive to the rotation of the outer sleeve 18 at extremely high speeds in an effort to dissipate the heat that is generated internally by friction with the pilot guide (not shown) as will appear more fully hereinafter. It should be noted that the outer sleeve 18 rotates with the inner sleeve 19 until they are connected by diametrically aligned points 31, in this instance two, that are pressed through somewhat smaller aligned apertures 32—33 provided in the outer and inner sleeves 18 and 19, respectively.

As shown, the inner sleeve 19 terminates in an enlarged circular flange 34 having an axially extending tubular boss 35 which is exteriorly threaded as at 36 to mesh with corresponding threads provided in a metallic bushing 37 comprising the core of a grinding wheel 38. The reduced tubular boss 35 together with the inner sleeves 19 have an aligned axial bore 39 which extends toward the upper tool holder ring 14 to communicate with a counterbore 40 that is somewhat smaller in diameter than the tool holder ring receiving recess 16 to communicate therewith to define the peripheral shoulder 17 serving as a seat for the tool holder ring 14.

An elongated pilot stem or guide receiving sleeve bearing 41 is press-fitted into the inner sleeve bore 39 to extend inwardly for a substantial portion of the inner sleeve 19. The sleeve 41 rotates with the outer and inner sleeves 18—19 and relative to a pilot guide or stem that extends from the valve stem bore in an engine cylinder head or from a grinding wheel dressing stand. This relative rotation generates appreciable heat which is conducted from the sleeve bearing 41 to the inner sleeve 19 and to the outer sleeve 18 for dissipation and cooling by the air circulating therebetween through the outer sleeve slot or flute passages 28—29—30.

A driver knuckle engaging disc 42 is confined for axial movement within the counterbore 40 to engage the lower circular edge of the tool holder ring 14. The disc 42 is yieldingly urged toward the tool holder ring 14 by a coil spring 43 confined in an end bore 44 of the inner sleeve 19 to rest against the sleeve bearing 41. In order to center the driver knuckle 11 on the spring supporting disc 42, the latter is provided with an axial aperture 45 which is somewhat larger than the tip 12 of the knuckle 11 for reception therein.

In order to preclude accidental detachment between the driver knuckle 11 and the outer socket

13, the latter is provided with an annular groove 46 proximate to the upper open edge 47 thereof to receive a split wire ring 48. The split wire ring 48 is of somewhat lesser diameter than the annular groove 46 so that the inner circumferential edge thereof will lie within the exterior confines of the socket 13 with sufficient space in the annular groove 46 to permit the outward expansion of the ring 48. Consequently, the largest diameter of the driver knuckle 11 will be somewhat greater than the normal inside diameter of the split wire ring 48 to cause the latter to expand responsive to the displacement of the driver knuckle 11 therethrough for registry with the socket 13 when the driver knuckle tip 12 is within the axial aperture 45 of the spring supported disc 42.

In this position the larger diameter of the knuckle 11 will pass beyond the split ring 48 which will then contract to its normal diameter over the driver knuckle 11 and precludes its accidental removal from the socket 13 and still permit its insertion therein without any appreciable difficulty. This arrangement affords a simple and inexpensive spring retainer for the driver knuckle 11 when it is in its operative position of full registry with the outer sleeve holder cap socket 13. With the arrangement of parts above described, simple and dependable expedients have been provided to maintain the driver knuckle 11 in registry with the socket 13 against accidental displacement for positive rotation of the outer sleeve 18 and inner sleeve 19 which are air cooled to effectively dissipate generated heat. The outer sleeve is preferably though not essentially constructed of high heat conducting material such as aluminum to hasten the heat dissipation in conjunction with the air circulating expedient provided therein.

Various changes may be made in the embodiment of the invention herein specifically described without departing from the invention or sacrificing any of the features or advantages thereof and nothing herein shall be construed as limitations upon the invention, its concept or structural embodiment as to the whole or any part thereof except as defined in the appended claims.

I claim:

1. In a device of the character described, the combination with an outer driving sleeve body, a tubular pilot receiving sleeve concentrically disposed in said driving sleeve body for rotation therewith, and means in said outer driving sleeve body to circulate air therein for dissipating generated heat responsive to the rotation thereof.

2. In a device of the character described, the combination with an outer driving sleeve body, an inner sleeve connected to said outer sleeve body for rotation therewith, and means between said outer driving sleeve and inner sleeve to circulate air therein for dissipating generated heat responsive to the rotation thereof.

3. In a device of the character described, the combination with an outer driving sleeve body, an inner sleeve connected to said outer sleeve body for rotation therewith, and elongated air vanes between said outer driving sleeve and inner sleeve to circulate air therein for dissipating generated heat responsive to the rotation thereof.

4. In a device of the character described, the combination with an outer driving sleeve having an annular groove proximate to one end thereof, there being elongated passages in said sleeve to communicate with said annular groove, said

sleeve having openings or ports therein proximate to the other end thereof to communicate with said air passages, and means for rotating said sleeve to effect the passage of air through said passages responsive to the rotation thereof.

5. In a device of the character described, the combination with an outer driving sleeve having an internal bore, there being an annular groove proximate to one end thereof, there being elongated passages in said internal bore of said sleeve to communicate with said annular groove, said sleeve having openings or ports therein proximate to the other end thereof to communicate with said air passages, and means for rotating said sleeve to effect the passage of air through said passages responsive to the rotation thereof.

6. In a device of the character described, the combination with an outer driving sleeve having an internal bore, there being an annular groove proximate to one end thereof, there being elongated passages in said internal bore of said sleeve to communicate with said annular groove, said sleeve having openings or ports therein proximate to the other end thereof to communicate with said air passages, an internal sleeve pressed into said outer sleeve bore to confront said elongated passages, and means for rotating said sleeve to effect the passage of air through said passages responsive to the rotation thereof.

7. In a device of the character described, the combination with an outer driving sleeve having an internal bore, there being an annular groove

proximate to one end thereof, there being elongated passages in said internal bore of said sleeve to communicate with said annular groove, said sleeve having openings or ports therein proximate to the other end thereof to communicate with said air passages, an internal sleeve pressed into said outer sleeve bore to confront said elongated passages, a pilot stem receiving sleeve bearing pressed into said inner sleeve for rotation therewith relative to a pilot stem, and means for rotating said sleeve to effect the passage of air through said passages responsive to the rotation thereof.

8. In a device of the character described, the combination with an outer driving sleeve having an internal bore, there being an annular groove proximate to one end thereof, there being elongated passages in said internal bore of said sleeve to communicate with said annular groove, said sleeve having openings or ports therein proximate to the other end thereof to communicate with said air passages, an internal sleeve pressed into said outer sleeve bore to confront said elongated passages, a pilot stem receiving sleeve bearing pressed into said inner sleeve for rotation therewith relative to a pilot stem, a socket in the driving end of said outer sleeve, and means complemental to said outer sleeve socket for rotating said sleeve to effect the passage of air through said passages responsive to the rotation thereof.
